United States Patent Office.

JOHN H. PHILLIPS, OF WASHINGTON, DISTRICT OF COLUMBIA.

Letters Patent No. 97,224, dated November 23, 1869.

IMPROVED CONSTRUCTION OF RAILWAYS.

The Schedule referred to in these Letters Patent and making part of the same.

To all whom it may concern :

Be it known that I, JOHN H. PHILLIPS, of the city of Washington, county of Washington, and District of Columbia, have invented a new and improved Mode of Constructing a Railroad or Permanent Way; and I do hereby declare the following to be a full, clear, and exact description thereof, reference being had to the accompanying drawings, and to the letters of reference marked thereon, in which—

Figure 1 is a perspective view of a section of the same, constructed in the manner hereinafter described.

Figures 2 and 3 are transverse vertical sections through the centre of the chairs, showing the adaptability of the chair to either the T or ordinary flanged rail.

Figure 4 represents the mode of bolting either form of rail to the chair on separate sides of the track, dispensing with the continuous tie *d*.

Figure 5 is a longitudinal vertical section through ear *a* and chair A.

In the construction of railways, the use of wooden ties or sleepers, must shortly, in the natural course of events, be abandoned for want of material to supply the demand, and in many countries, and even certain sections of the United States, at the present time, the desired quality can only be obtained by transporting it such a distance as to render its cost nearly if not quite equal to that of other material, such as iron and stone, which is often to be found where timber is most scarce, and which, though more costly in most localities at present, would, even in such localities, be found most economical in the long run, on account of its permanency and durability.

Difficulties have, however, been heretofore experienced in the use of such materials: first, in securing the rail to the stone, on account of the continual jar upon the rail, tending to draw the spikes; and secondly, on account of the unyielding nature of the material, when solidly bedded, being injurious to the rolling stock, it having been satisfactorily demonstrated that a certain amount of flexibility in the road is necessary to its durability, and also to that of the rolling stock employed thereon.

My present invention consists in a novel construction of the substructure of a railway, composed of stone, concrete, or iron chairs, bound together by iron ties, and so fashioned as to support and hold the rails firmly together and in place.

To enable others skilled in the art to make and use my invention, I will proceed to describe its construction and operation.

A A are solid stone, concrete, or cast-iron concavo-convex sills or chairs, of form and size best adapted to give strength and solidity to the substructure of the road. In the present case, it will only be neces-

sary to describe the application of iron chairs, which have cast with and upon the outer surface of the same, two projections or ears, *a* and *e*, forming a channel or groove, in which the rail rests.

These projections may be strengthened by ribs or braces, *bb*, and the chair itself may be likewise strengthened by other and additional ribs, extending from its apex radially downward on its external surface, and the point of greatest pressure at the centre of the chair, may, if found necessary, be similarly supported by the transverse rib *m*, on the under side. In the use of cast-iron chairs, as above described, sufficient elasticity may be secured to the rail, from the convex form of the chair, the more especially, that while it tends constantly and firmly to clutch and become part of the bed of the road, it will have the elastic force of the necessarily-compressed air between its inner upper surface and the bed beneath.

But to remedy any possible deficiency in the amount of elasticity required, I propose the packing *k* of wood, rubber, or other suitable material, in a cell, constructed on the top of the chair for the purpose, and secured in place beneath the rail by shoulders *f*; and in order to give elasticity of motion to the rail, the perforation in the rail through which the tie *d* passes, should be slightly elongated vertically; and to insure an even bearing of the rail longitudinally, and prevent the packing *k* from displacement, the bottom of the cell should be curved concentrically with the upper part of the chair, and the packing correspondingly shaped on its under side, so as to be thicker at its two ends than in the middle.

The outer ear *a* of the chair, and the corresponding point of the rail in the aforesaid groove, are perforated for the passage through the same of the tie *d*.

This tie may be wrought in one piece, with collars *h h* at suitable and equal distances apart, so that when in place, the respective collars may come flush with, or have an equal bearing against the inner side of the rails.

A nut, *i*, is then screwed upon the outer end of the tie, bearing firmly against the ear *a*, thus holding the rail and chair together, and if need be, may be secured to its place by a key passing through a slot in the outer-projecting end of the tie. It will thus be seen that the displacement of the rail is impossible.

The sill opposite may be so constructed as to admit the other end of the tie to drop into position through a dovetail-shaped opening, *r*, and a dovetail key afterward inserted therein, and then bolted. If stone or concrete chairs be employed, the strain upon the outer ear may be readily resisted, by enlarging its dimensions.

Roads constructed on this plan, may use either the T-shaped or the ordinary flanged rail. In the latter

case, the channel of the chair must be adapted, in shape, to the form of the rail, but I prefer the former, as represented in fig. 3.

In connection with the flanged rail, a form of tie, as shown at *x*, may be used, in which case, the rail and sill are bolted together on each side of the track separately, and not by the continuous tie *a*. Said tie *x* consists of a broad metallic bar, with its ends so shaped as to hook on the outer flanges of the rail, and, by means of clips bolted over the inner flanges, keeps the rails at a uniform distance apart, and at the same time binds them together. Where the rails join, the ears may be sufficiently enlarged to admit of a double tie.

A road thus constructed, will embrace, among others, the following advantages: The periodic renewal of

wooden ties, and the use of spikes and connecting chairs will be avoided; the rail will be held firmly in place with little if any possibility of displacement, and additional security to life be thus afforded, whilst the necessity of constant surveillance with attending expenses, will be almost entirely dispensed with.

Having thus fully described my invention, What I claim as new, and desire to secure by Letters Patent, is—

The wrought-iron tie-bar *d*, in combination with the rail, and bed-block *A*, constructed and arranged as and for the purpose specified.
